CLAIM

The ornamental design for an interactive device for a user, as shown and described.

DESCRIPTION

FIG. 1 is a top and front perspective view of an interactive device for a user showing our new design;

FIG. 2 is a front elevational view thereof;

FIG. 3 is a bottom and front perspective view thereof;

FIG. 4 is a top and left perspective view thereof;

FIG. 5 is a left perspective view thereof;

FIG. 6 is a bottom, front and right perspective view thereof;

FIG. 7 is a top and right perspective view thereof;

FIG. 8 is a right elevational view thereof;

FIG. 9 is a bottom and rear perspective view thereof;

FIG. 10 is a top plan view thereof; and

FIG. 11 is a bottom plan view thereof.

FIG. 12 is a top and front perspective view of a second embodiment of an interactive device for a user showing our new design;

FIG. 13 is a front elevational view thereof;

FIG. 14 is a bottom and front perspective view thereof;

FIG. 15 is a top and left perspective view thereof;

FIG. 16 is a left perspective view thereof;

FIG. 17 is a bottom, front and right perspective view thereof;

FIG. 18 is a top and right perspective view thereof;

FIG. 19 is a right elevational view thereof;

FIG. 20 is a bottom and rear perspective view thereof;

FIG. 21 is a top plan view thereof; and,

FIG. 22 is a bottom plan view thereof.

The broken lines represent disclaimed portions and form no part of the claimed design.

1 Claim, 22 Drawing Sheets
